PRINTING TELEGRAPH SYSTEM

Harry J. Nichols, Dayton, Ohio, assignor to International Business Machines Corporation, New York, N. Y., a corporation of New York

Application October 27, 1934, Serial No. 750,285

21 Claims.

(Cl. 178—4)

This invention relates to a printing telegraph system and particularly to a printing telegraph system for the transmission of statistical information and the like.

The invention is described mainly with reference to a system for the telegraphic transmission of the essential information on bank credits, but it is generally applicable to the transmission of such data as can be initially transcribed in the form of marks placed on or holes punched 5 into cards in predetermined coded similar space relationship, in general form to the well known tabulating card.

It is the principal object to provide a system for the transmission of intelligence of the character of arbitrary indications arranged in predetermined coded position on a record card or the like.

It is a further object of the invention to provide a method and apparatus whereby statistical information, comprising for example mainly numeral groups with such figures and signs as may be required to render the numeral groups intelligible, may be transmitted and reproduced at a 20 distance by electrical means with perfect accuracy and great rapidity.

It is a further object to provide a system adapted to effect the rapid, economical, and safe exchange and clearance of bank credits by telegraphic methods.

Other objects and features will be in part obvious and in part hereinafter pointed out in connection with the following description, the accompanying drawings, and the appended claims.

In the drawings:—

Fig. 1 shows a form of record card adapted for use in connection with the invention.

Fig. 2 shows the record card of Fig. 1 in position for scanning.

Fig. 3 shows schematically in cross-section the 40 automatic transmitter forming a part of the invention.

Fig. 4 shows in schematic form the electrical circuits of the transmitter shown in Fig. 3.

Fig. 5 is a detailed view of the switching mechanism by which proper scanning of the record card is secured.

Fig. 6 shows in schematic form the general arrangement of the mechanism of the reprinter.

Fig. 7 shows in schematic form a diagram of 50 electrical circuits of the reprinter, the series of cams of Fig. 6 being shown in exploded view in order to clarify the diagram.

Fig. 8 is an end view in part section of the mechanism of Fig. 6, illustrating particularly 55 the printing mechanism.

Fig. 9 shows in end view details of the mechanism by which the typewheel of Fig. 6 is shifted to change the case of printing.

Fig. 10 shows a section of the printed tape indicating the form in which the received information is presented; and

Fig. 11 shows a modification of the arrangement of Fig. 3.

In the several figures, like characters represent like parts.

The present invention provides for the transmission of intelligence of any desired sort, but is arranged more particularly for the transmission of statistical data. For example the invention provides a system for the transmission of any of the types of information commonly contained on tabulating cards and the like. In such cards the information is arranged in the form of arbitrary indications coded according to their position on the card. The indications may be in the form of holes punched into the cards or 20 in the form of marks of contrasting color or reflection characteristics with respect to the remainder of the card.

As a particular application the invention may be applied to the transfer of credit, as between 25 banks or similar institutions. In accordance with the existing practice, credit is transferred largely by way of the mail necessitating a material time during which the credit is in large part unavailable to any party. This credit in course 30 of transfer is termed the "float", and involves a loss of income of quite material proportions. In accordance with the present invention the "float" can be materially reduced by a rapid, accurate and inexpensive written communication transferring credit. The invention accordingly is described with reference to such a system, for illustrative purposes. The system is further described in detail as using record cards in which the data is in the form of punched holes in the 40 card but it is evident that it is equally applicable with slight modification for use with cards where the data is in different forms, such as contrasting color or the like.

Referring now to Fig. 1, a special form of draft or acceptance adapted to the purposes of the invention is shown, although it is to be understood that the record card used for transmission may have any form suitable to the transaction or data to be transmitted. In the present instance, for 50 illustrative purposes, it is assumed that a particular bank whose code number is 56—30 wishes to transfer credit of one thousand dollars to another bank whose code number is 7—82. Bank 56—30 has prepared a record card as shown, duly 55

filled out on one part, then coded as shown in a suitable card punching machine on the remaining part, and after verification and recording, has been signed by the proper official if so desired. The essential information, such as identifying number of transferor and transferee, the amount of the transfer, and the serial number of the transfer itself if desired, are thus recorded in punched holes. The completed card is placed 10 in the transmitter, and by means not shown is brought to a predetermined position for transmission.

The coded information is recorded in a part of the card termed the field, and is arranged in 15 vertical columns, and in horizontal levels or lines in the manner of the well known tabulating card. The position of each punched hole represents a numeral or its associated sign, with an additional line in each column in which a shift operation for 20 the selection of signs is recorded, thus providing twenty characters in all. The blank space at the top of the card represents the scanning interval in which a synchronizing signal is transmitted. The field may be blank, or may be printed to indicate 25 the interpretation of the coded positions, thus permitting of visual verification.

Referring now to Fig. 2, the record card 1 is shown in position for scanning, such scanning forming part of the transmission process. The 30 coded field of the card is immediately over scanning belt 2 of the transmitter, presently to be described. The scanning belt is provided with a series of scanning holes 2a, one for each column of the field, arranged in echelon, being separated 35 along the length of the belt by a distance equal to the height of the record card, and across the width of the belt by a distance equal to the median distance between columns on the card. The belt, which is endless, is provided with a 40 single registry hole 2b, and along one or both margins with a continuous series of equally spaced driving holes 2c. The belt is driven in uniform continuous motion by a sprocket wheel in the direction shown. It will be apparent that 45 in one complete revolution of the belt, the scanning holes will pass in proper sequence under each of the vertical columns of the record card.

Referring to Fig. 3, the scanning mechanism has for its main elements a light source 11, a light 50 reactive device or photo cell 12, scanning belt 2, and the drive means therefor. Light source 11 is suitably mounted in a reflector 13 which directs the light in a parallel beam upon the code field of record card 1 and towards photo-cell 12. 55 Photo-cell 12 is mounted at the focus of parabolic reflector 14 so as to receive the maximum of light on its sensitive surface. At the instant a scanning hole is coincident with a hole in the card, a beam of light passes from the light source 60 to the photo-cell, energizing the latter, and by means later to be described, causing a signal impulse to be transmitted. Thus by the passage of the scanning belt beneath the card, timed impulses are transmitted in accordance with the 65 information coded in the punched holes of the record card.

Scanning belt 2 is driven at a uniform rate by a sprocket wheel 15, which in turn is driven by a motor (not shown). The scanning belt is held 70 taut in position by idler pulleys 16b. A transparent table 17 is shown as supporting record card 1, but this table is optional, the card being supported directly by the scanning belt if preferred.

75 Sprocket wheel 15 is provided with a cam 18

fixed on one end of its shaft, this cam being provided with a single rise or lobe 18a which closes contacts 19 momentarily once during each revolution of sprocket wheel 15. As will be more fully described hereinafter, the closing of contacts 19 5 generates the synchronizing signal which is transmitted over the line to the receiving apparatus for synchronizing purposes. The effective circumference of sprocket wheel is exactly equal to the height of the record card, hence a synchronizing signal is sent out for each traverse of the 10 card by a scanning hole. The scanning belt is so placed in the sprocket that the synchronizing signal is sent to the line at a time when the scanning holes pass the blank margin of the 15 card. Hence the synchronizing signals do not interfere with the printing signals, and vice versa.

Since the scanning belt is preferably kept in continuous motion, means are provided to ensure 20 that the card will always be scanned in the proper order, that each card will be scanned but once, and that false signals will not be sent to the line when the card is being moved into or out of position, or in the absence of a card. The 25 means for accomplishing these various safeguards comprise a card switch 21, shown in Fig. 4, and an automatic sequence switch 22 shown in Figs. 4 and 5.

Card switch 21 is connected in a circuit comprising battery 23, lift magnet 24, and a reading condenser arrangement comprising capacitor 25 and resistor 26 in parallel. The contacts of card switch 21 are normally closed, but when a card is fully inserted and in position for scanning, the 35 card slips between the contacts of card switch 21, breaking the circuit including the winding of lift magnet 24.

Referring now to Fig. 5, sequence switch 22 is mounted on lever 31, and its contacts are normally open as shown. Lever 31 is pivoted about 40 axis 32, and carries at its free end star wheel 33 and a double lobed cam 34 fixed to the shaft of star wheel 33, their common shaft being journaled in lever 31. Sprocket wheel 15 has a cylindrical barrel in which are machined spaced longitudinal grooves or flutes as shown. These grooves are adapted to catch the points of star wheel 33 when the register hole 2b in scanning belt 2 passes underneath the star wheel. The 45 belt normally prevents the star wheel from being engaged by the flutes in the barrel of the sprocket wheel, but once each revolution the aforementioned register hole permits one point of the star wheel to drop into engagement with the barrel of the sprocket wheel. The register hole is located 50 in the scanning belt in such relation to the scanning holes that the first scanning hole is just entering on its traverse of the card when the register hole passes beneath the star wheel. This 55 relationship of register hole and first scanning hole is indicated in Fig. 2.

The operation of the sequence switch is as follows:—Before entry of a card for scanning, lift magnet 24 is energized and lifts the free end 60 of lever 31 so that star wheel 33 is withheld from contact with the scanning belt. The contacts of sequence switch 22 are then open, and no potential is applied to the photo-cell. (See Fig. 4.) When the card is inserted, the contacts of card 65 switch 21 are forced apart, lift magnet 24 is de-energized, and star wheel 33 is lowered into contact with the scanning belt. When the register hole passes beneath star wheel 33, the leading 70 point of the star wheel drops through the hole 75

and is caught by the edge of one of the grooves. The rotation of the sprocket wheel carries the point of the star wheel backwards, rotating star wheel 33 one quarter turn counter-clockwise as viewed. Cam 34, fixed to the shaft of star wheel 33, is likewise rotated one quarter turn, and permits the contacts of sequence switch 22 to close, thus applying potential to photo-cell 12. The scanning of the card then ensues. At the 10 end of the scanning, which constitutes one revolution of the scanning belt, the register hole again passes beneath the star wheel, the star wheel is tripped, cam 34 opens the contacts of switch 22, and potential is removed from the photo-cell. 15 Shortly thereafter, the card is ejected from the transmitter by means not shown but preferably coordinated with the scanning belt so that the card is automatically and positively ejected at the proper point of the scanning cycle, permitting 20 the contacts of card switch 21 to close, energizing lift magnet 24 which lifts star wheel 33 away from the scanning belt. Upon the insertion of another card, the cycle of operations just described is repeated. It is thus seen that 25 the cooperation of the card switch and sequence switch provide the proper safeguards in the scanning process.

Referring to Fig. 4, the principal components of the sending apparatus of the transmitter consist of photo-cell 12, electronic-relay 40, cut-out relay 41 associated therewith, battery 23, line transformer 43, and line 44. Electronic-relay 40 is preferably of the gaseous discharge or grid-glow type, having a plate 40a, grid 40b, and cathode 40c all enclosed in a glass envelope in the usual manner. Photo-cell 12 may be any suitable type of light reactive device, and is shown in the conventional manner as consisting of an anode 12a and cathode 12c. Battery 23, or other source of direct current, furnishes a positive potential to the anodes of the electronic-relay and photo-cell. Photo-cell 12 is connected in the cathode-grid circuit of the electronic relay, and a trip-circuit consisting of cam switch 19 and current limiting resistor 45 are connected in parallel therewith. The function of cam switch 19 is to trip electronic relay 40 for an instant during each revolution of drive sprocket 15. Sequence switch 22 is connected in series with 50 photo-cell 12, rendering the same ineffective when its contacts are open. Capacitor 42 has a stabilizing effect on the electronic relay. The plate-cathode circuit of electronic relay 40 includes battery 23, the primary of line transformer 43, and the winding of cut-off relay 41.

The operation of the sending apparatus is as follows:—Considering first the generation of synchronizing signals, when cam 18 closes switch 19, the potential of grid 40b is raised by reason 60 of being momentarily connected to the positive side of battery 23. As is well known, raising the grid of a grid-glow tube to a positive potential “trips” the tube, i. e., causes it to become ionized, the tube becomes conducting, and a markedly 65 increased plate current flows. In the present instance, the increased plate current flows through the primary of line transformer 43 and an impulse is sent to the line. As the plate current approaches its maximum, cut-off relay 41 is energized, opening its contacts and cutting off 70 the plate current. The current flow is interrupted for a period sufficient for the electronic relay to de-ionize. Meanwhile, contacts 19 have opened, restoring grid 40b to its normal potential.

Considering now the sending of printing signals, it is to be assumed that a record card is in position for scanning, and that the contacts of sequence switch 22 are closed. When a scanning hole moves into coincidence with a punched hole 5 on the card, a light beam passes from light source 11 to photo-cell 12, energizing same. As is well known, the effect of increased light striking a photo-cell is to decrease its resistance. Hence the potential of grid 40b is raised, since the anode 10 12a of the photo-cell is connected to the positive side of battery 23. Electronic relay 40 is thus tripped, a current impulse is generated in its plate circuit, and a signal is sent to the line as previously described. The current impulse is 15 terminated by the cut-off relay as in the previous case, hence the synchronizing signals and printing signals are of like duration and amplitude. It is to be noted, however, that while the synchronizing signals are periodic, the printing signals 20 are aperiodic, the time of their occurrence being established by the position of the punched holes in the record card.

Referring now to Fig. 6, in which the mechanism of the receiving printer, termed the re-printer, is shown. Drive motor 50, of uniform speed characteristics, drives drive shaft 52 through reduction gear 51 whereby the drive shaft is caused to rotate at the same speed as sprocket wheel 15 at the transmitter. In the 30 system described, it is essential that the type wheel 53, and other elements of mechanism concerned with the printing function move in synchronism with the scanning mechanism, that is to say, it must move at the same rate, and with 35 a particular phase relationship thereto. Type wheel 53 and the other synchronous elements are therefore carried on printer sleeve 54, rotatably mounted on drive shaft 52. Intermediate drive shaft 52 and printer sleeve 54 is phase corrector 40 mechanism 55, including a friction coupling not shown. Printer sleeve 54 can be stopped while drive shaft 52 is in rotation by armature 56a of release magnet 56 engaging stop arm 54a. Also, while in rotation, printer sleeve 54 can be rotated 45 relative to drive shaft 52 by phase corrector mechanism 55 which functions to advance or retard the phase of printer sleeve 54 with respect to shaft 52 in accordance with the synchronizing impulses, to thereby maintain the sleeve in synchronism with the scanning mechanism. While 50 any suitable form of phase corrector mechanism may be used, the preferred form for use with the mechanism of the invention is that described in my co-pending application Ser. No. 736,383. 55

Printer sleeve 54 carries a series of five fixed sequence cams, designated by 57a to 57d inclusive, worm 58, paper-feed cam 59, and type wheel 53. Type wheel 53 is splined on printer sleeve 54, i. e. it is slidably axially thereon but is fixed 60 as to rotation by a groove and key, or other preferred construction. Printer sleeve 54 is secured in frictional driving relation on drive shaft 52 by washer 61 and nut 62, the latter also serving to adjust the pressure on the friction coupling. 65

The method of synchronizing printer sleeve 54 is as follows:—In the absence of synchronizing signals, release magnet 56 is un-energized, and its armature 56a drops away, intercepting stop arm 54a and stopping sleeve 54 in a predetermined position in which cam 57b closes contacts 67b, the drive shaft being permitted to continue 70 in rotation by reason of the friction coupling. Referring now to Figs. 6 and 7, which latter shows the electrical circuits of the reprinter and 75

the sequence cams and contacts in exploded position, and assuming that the transmitter sends synchronizing signals as previously described, when a synchronizing signal is received, electronic relay 70 is tripped, and current flows from positive battery via windings of magnet 56, contacts 67b, plate to cathode of electronic relay 70, via windings of cut-off relay 71 and return to negative battery. Release magnet 56 is energized by the current pulse through the circuit just traced, releasing stop arm 54a, whereupon printer sleeve 54 is placed in rotation at the speed of drive shaft 52 by means of the friction coupling. Co-incidentally, cut-off relay 71 is energized, interrupting the flow of current in the plate circuit. Magnet 56 is provided with a storing capacitor 56c of considerable capacity, and energy stored therein provides holding current for magnet 56 during the normal interval between synchronizing impulses. Thus magnet 56 is sustained in operated position so long as synchronizing signals are regularly received; otherwise it drops out, stopping arm 54a. The corrector mechanism now operates to bring printer sleeve 54 into exact unison with the synchronizing impulses, and as will be more fully explained hereafter, thereafter corrects as necessary the phase position of sleeve 54 to maintain unison.

Referring now to Fig. 8, printing is accomplished whenever printer magnet 80 is energized, printer hammer 81 being driven towards the type wheel by the pull-in of armature 80a. The length of printer hammer 81 and the travel of armature 81a are so regulated that printer hammer 81 is carried through to the end of its stroke only by the inertia stored therein by its preceding motion. The current through magnet 81 is comparatively strong, and its inductance is low in order that armature 81a may have a quick stroke. Thus printer hammer 81 drives the tape 82 against the type wheel 53 with a sharp blow, the rebound throwing the printer hammer back quickly so as to avoid smudging the impression. A flexible extension 80b on armature 80a also lifts the fork 83 of the automatic paper feed mechanism.

50 In order to obtain characters additional to numerals without increasing the number of printing arcs, a second series of characters are provided on the type wheel parallel to and twin-
55 ning with the numerals. Since the printing po-
sition is fixed, the type wheel must be moved the correct amount in an axial direction in order to print the additional characters, which for exam-
ple will be referred to as signs. Since a large proportion of the printing is in numbers, one of the features of the invention is the means by which the type wheel is shifted to print signs, and automatically returned to print numerals. Thus
60 only one line signal is required to effect shifting, while unshifting is effected without signal, econ-
omizing on line time. When a sign, as for ex-
ample the \$ sign, is to be recorded, the per-
forating machine operator depresses the shift
65 key which automatically punches a hole at the head of a column, and then the number key hav-
ing the \$ subscript, whereupon a second hole is punched in the column at the proper numeral position. On transmission, a shift signal is trans-
70 mitted by the hole at the head of the column, and a printing signal at the numeral position as usual. At the reprinter, the shift signal is re-
ceived when cam 57d has closed contacts 67d, which causes shift magnet 87 to be energized by electronic relay 78. Magnet 87 pulls in pivoted

armature 87a on the free end of which is a roller 87b which moves into a position of engagement with a side cam 53a on type wheel 53. (See Figs. 6 and 9.) Cam 53a immediately strikes roller 87b, and type wheel 53 is shifted axially to the right as viewed in Fig. 6 and remains in this position until near the end of a revolution. While so shifted, the printing signal is received at the proper instant, the printing hammer 81 is actuated in the manner already described, and \$ is printed. Near the end of the revolution, side cam 53b on the other edge of type wheel 53 engages stationary roller 88 and the type wheel is cammed back to its normal position.

The tape feed mechanism (see Figs. 6, 7 and 8) 15
comprises a ratchet wheel 90, idler rollers 91, pawl
lever 92, feed cam 59 (carried on printer sleeve
54), pawl holding magnet 93, control switch 94,
and operating means for the control switch pres-
ently to be described. Tractile spring 95 nor-
mally holds pawl lever 92 in engagement with
cam 59, and pawl 92a successively engages the
teeth of ratchet wheel 90, advancing the tape one
step for each revolution of feed cam 59. The
advance of the tape occurs in a non-printing 20
interval, that is between the scanning of one col-
umn and the next. The tape is drawn along by
a light friction, so that the tape can slip a trifle
during the instant of printing thus avoiding
blurring on the type wheel. Furthermore, the 25
tape can be pulled out and torn off at will.

The control of the tape feed is as follows:—
Printer sleeve 54 carries worm 58 which is in continuous rotation. Control arm 96, pivoted on support 97, is movable sideways and upwards, but is drawn to the left and downwards by tractile spring 98. A pin 96a at the free end of arm 96 engages worm 58, thereby moving the control arm to the right against the action of the tractile spring. When arm 96 is moved to the extreme right, a knob 96b closes contacts 94. Normally, however, printer magnet 80 is energized before arm 96 reaches the point of closing contacts 94, and arm 96 is raised by fork 83 and returned to the left by the tractile spring. Thus arm 96 is continually returned to the left position during the printing interval, contacts 94 remain open, and cam 59 once each revolution advances the ratchet wheel one tooth, feeding the tape the proper amount for printing. If a column on the record card has no punched hole, the tape is advanced one notch, leaving a blank. Therefore, no paper feed or space signal is required. When the printing signals cease for an interval longer than that required for 5 or 6 revolutions of worm 58, arm 96 reaches its extreme right position, contacts 94 are closed, and holding magnet 93 is energized. When cam 59 next oscillates pawl lever 92, this lever is retained by holding magnet 93, and the pawl is not permitted to gather in the next tooth of the ratchet. Magnet 93 is provided with a storing capacitor 93a so that pawl lever 92 will not be released by a momentary opening of contacts 94 due to the irregular nature of the worm thread end. Feeding of the tape thus ceases five or six spaces after the printing of the last character, and is not resumed until a printing signal is received to release arm 96. The several spaces at the end of the printing provide a lengthened space between messages, and provide room for tearing off the tape.

It will be clear that the feature just described has the multiple advantages of not requiring a spacing signal, of obtaining the energy for the tape feed from the motor thus avoiding the need

for a powerful paper feed magnet, provides a lengthened space between messages, and conserves tape when printing signals are not being received.

5 Fig. 10 shows a sample of the tape with an illustrative message.

Referring again to Fig. 7, the sequence of operations of the printer cams is as follows:—Considering the operations as they occur in order 10 from the initiation of a scanning cycle, cam 51a closes contacts 67a momentarily just before the synchronizing signal is due. If the reprinter is running slow, the synchronizing impulse will in part be applied through the circuit from positive 15 battery through winding of magnet M1 via contacts 67a, electronic relay 10, through winding of cut-off relay 11, and return to negative battery. M1 will thus be energized, actuating the phase corrector mechanism which during the succeeding 20 revolution of printer sleeve 54 will advance its phase a predetermined amount, thus restoring perfect unison.

Cam 51b closes contacts 67b just as contacts 67a open, hence part of the synchronizing impulse 25 will pass through the circuit including release magnet 56, whose storing capacitor 56a will be recharged, sustaining magnet 56 in the operated condition.

Cam 51c closes contacts 67c just as contacts 67b open, hence if the printer sleeve were running slightly fast, corrector magnet M2 would be energized, causing the phase corrector mechanism to retard the phase of the printer sleeve a predetermined amount, thus restoring unison. Normally, 30 when the reprinter is in unison with the transmitter, the entire synchronizing impulse goes to restore the charge on capacitor 56a.

Shortly after contacts 67c open, cam 51d closes the contacts 67d. Should a shift signal be received 40 at this moment, shift magnet 87 would be energized, and the typewheel 53 shifted as previously described. Should there be no shift signal, electronic relay 10 is not tripped, hence shift magnet 87 would not be energized.

45 After being closed for a brief interval, contacts 67d open and contacts 67e, which up until this time have been open, are closed by cam 51e, to remain closed during the remainder of the printing cycle. Should a printing signal be received, printer magnet 80 is momentarily energized before cut-off relay 11 interrupts the circuit, and a character is printed as previously described. Since the proper unison, as provided for, typewheel 53 rotates in step with the scanning of the 50 record card, the character printed will correspond with that punched in the record card.

It is to be noted that the operating impulses at the printer are controlled in duration by the cut-off relay 11, which is provided with suitable 60 timing arrangements. Thus the duration of the operating impulses is independent of the received signals to a considerable extent, and the printing impulses can be timed so as to provide a margin of operation, termed the synchronizing margin. 65 It is further to be noted that the cam operated contact arrangement is the equivalent of the rotary distributor commonly used in synchronous printing telegraph systems. A rotary distributor could in fact be substituted for the cam operated contact arrangement without changing the mode of operation of the system as described, the arrangement shown being preferred because of its simplicity and small size.

In the foregoing description, the reprinter has 70 been described as a typewheel, tape printer.

Other forms of receiving apparatus may be used, as for example, a reperforator may be employed as the receiving instrument, the received record taking the form of a punched tabulating card similar to the transmitting record card.

In case the data on the record card is indicated by marks or dots, rather than punched holes, the scanning elements of Fig. 3 are preferably rearranged so that the photo-cell is actuated by reflected rather than direct light. For 10 example, in Fig. 11 which illustrates an embodiment adapted to scanning by reflection, the record card 1 is stationed on inclined table 17 below scanning belt 2 in such relation to photo-cell 12 that light passing from light source 11 through 15 scanning hole 2a and falling upon record card 1 will be reflected to the sensitive surface of photo-cell 12, as indicated. Thus as scanning belt 2 moves through a scanning cycle, a moving spot of light passes sequentially over the field of the record card, and the light link from light source 11 to photo-cell 12 is varied in accordance with the reflected light. In the event the field of the record is light in color, as for example white, and the record marks dark, as for example black, 20 the photo-cell 12 will normally receive maximum light when the scanning spot is passing between record marks, and reduced light when passing over a record mark. By well known means, the photo-cell may be caused to trip the 25 electronic relay on a reduction, rather than an increase of received light, as required in the instant case.

While the methods herein described and the forms of apparatus for carrying these methods 30 into effect, constitute preferred embodiments of the invention, it is to be understood that the invention is not limited to these precise methods and forms of apparatus, and that changes may be made in either without departing from the scope 35 of the invention which is defined in the appended claims.

What is claimed is:

1. In a communication system of the character described, a record card containing intelligence in the form of arbitrary indications arranged in predetermined coded position thereon, a transmitter, means for causing operation of said transmitter to effect transmission of impulses timed in accordance with the position of said indications, and a receiving printer, and means controlled by said timed impulses for effecting predetermined operation of said receiving printer to record said intelligence in printed form corresponding with the original record card. 45

2. In a communication system of the character described, in combination, a record card containing intelligence in the form of arbitrary indications arranged in predetermined coded position, there being a separate indication for each character to be transmitted arranged distinctively as to position on said card transmission means controlled by said card including a moving scanning belt, a light source, and light reactive means controlled in response to cooperative positions of said scanning belt and said indications on said card. 60

3. In automatic telegraph transmitters, in combination, a record card containing intelligence in the form of arbitrary indications arranged in predetermined coded position, scanning means adapted to scan said card containing a plurality of said indications, light reactive means controlled by the cooperation of said scanning 65

means and said indications on said card, and signal transmission means including means for transmitting a reference signal and means including said light reactive means for transmitting a signal in predetermined timed relation with said reference signal and indicative of an indication in predetermined position upon said card.

4. In automatic telegraph transmitters, a record card containing intelligence in the form of 10 arbitrarily arranged indications, there being a separate indication for each character to be transmitted arranged distinctively as to position on said card, scanning means for said card, and means controlled by said scanning means for 15 transmitting said intelligence in the form of a timed impulse corresponding to each of said indications.

5. In automatic telegraph transmitters, in combination, a card containing intelligence in 20 the form of arbitrary indications arranged in predetermined coded position thereon, scanning means for said card, light actuated means responsive to the cooperation of said card and said scanning means, signal transmission means 25 controlled by said light actuated means and including means to initiate discrete and timed impulses corresponding to the indications scanned, and means for assuring a predetermined order of scanning of said card.

30 6. In automatic telegraph transmitters, in combination, a card containing intelligence in the form of arbitrary indications arranged in predetermined coded position, scanning means for said card, light actuated means responsive 35 to the cooperation of said card and said scanning means for generating aperiodic printing signals, and means controlled by the light responsive means to initiate discrete and timed impulses representing the signals corresponding to the 40 indications scanned and additional means for generating periodic synchronizing signals.

7. In automatic telegraph transmitters, in combination, a card containing intelligence in the form of arbitrary indications arranged in 45 predetermined coded position, scanning means adapted to scan said card containing a plurality of said indications, said scanning means including a scanning belt provided with a series of scanning apertures in echelon arrangement, 50 drive means for said scanning belt, a light source, light reactive means actuated in response to the cooperation of said scanning apertures and said indications, means for transmitting reference signals, and means for transmitting signals having 55 predetermined relation to said reference signals upon actuation of said light reactive means.

8. In automatic transmitters, in combination, a light source, a perforated record card containing intelligence in the form of holes arranged in 60 predetermined coded position, scanning means arranged to scan the surface of said card containing a plurality of said holes, and light reactive means actuated in response to the establishment of a light link from said light source to said light reactive means, and means controlling the energization of said light reactive means for assuring scanning of said card in predetermined sequence.

9. In automatic transmitters, a record card 70 containing intelligence in the form of arbitrary indications arranged in predetermined coded position, a light source, scanning means, light reactive means cooperating with said scanning means and actuated in response to the scanning 75 of said indications, a source of electrical energy,

electronic relay means adapted to be ionized in response to actuation of said light reactive means and to thereafter remain ionized independently of said light reactive means, and means for interrupting the flow of current from said source 5 of energy through said electronic relay means after ionization by said light reactive means.

10. In automatic transmitters, the combination of claim 9 and independent means adapted to ionize the electronic relay of claim 9. 10

11. In apparatus of the character described, in combination, a record card containing intelligence in the form of arbitrary indications arranged in predetermined coded position, a scanning means for said card, light reactive means responsive to the cooperation of said indications and said scanning means, and control means for said light reactive means adapted to render said light reactive means effective only during a predetermined sequence of scanning the record 20 card.

12. In a synchronous transcribing system, a record card containing data in the form of holes punched in predetermined positions, scanning means for said record card, means for generating 25 aperiodic signal impulses responsively to the cooperation of said scanning means and said record card, means for generating periodic synchronizing signal impulses related in time to said scanning means, transmission means for said periodic 30 and aperiodic signal impulses and synchronous receiving means adapted to translate said signal impulses into record form.

13. The method of transmitting statistical data which comprises placing the data in the form of 35 arbitrary indications arranged in predetermined coded position on a record card, scanning said card, generating aperiodic signal impulses responsively to the scanning of said record card and the position of said indications thereon, transmitting said impulses, and translating said aperiodic signal impulses into record form. 40

14. In telegraph printers, in combination, a synchronous element, constant speed drive means therefor, a plurality of circuit closing means 45 carried by said synchronous element, synchronizing means including said circuit closing means for controlling the driving of said synchronous element from said driving means, a typewheel carried by said synchronous element, a tape for 50 recording purposes, printing means, tape feed means adapted to feed and space the tape as required during printing intervals, and means for terminating the tape feeding operation a predetermined time after the ceasing of printing 55 signals.

15. In telegraph printers having a printer sleeve, the combination of a cam carried by said printer sleeve, step by step tape feed means actuated by said cam, and control means for said tape feed means for operating said tape feed means during printing intervals, and for continuing the operation of said tape feeding means for only a predetermined limited time following a printing operation. 60

16. In telegraph printers, a synchronous printer element, a type wheel carried thereby and slidable axially between a normal and an alternative position, and shift means for said type wheel adapted to shift said type wheel to said alternative position at the beginning of the cycle of operation of said printer element, said type wheel remaining in said alternative position during said cycle of operation independently of said shift means, and means operable at the end 70 75 75 of said shift means, and means operable at the end 75

of said cycle of operation for returning said type wheel to its normal position.

17. In telegraph printers, an electronic relay including a plate, and cathode and ionizable in response to received signals, a plurality of branch circuits in the plate-cathode circuit of said electronic relay, each branch circuit including the operating winding of a magnet, a synchronous printer element carrying a type wheel, and a plurality of circuit closing means carried by said synchronous printer element and adapted to close said branch circuits in predetermined sequence.

18. The combination of claim 17, and means independent of the circuit closing means for terminating the current in the plate-cathode circuit of said electronic relay upon ionization after a predetermined interval.

19. In automatic transmitters, in combination, a card containing intelligence in the form of arbitrary indications arranged in predetermined coded position, scanning means for said card, control means for assuring a predetermined order of scanning of said card, and means actuated by

said card to initiate operation of said control means when said record card is in proper position for scanning.

20. A system for transmitting statistical data comprising a card having said data arranged thereon in the form of arbitrarily positioned indications, an electronic relay ionizable in response to received signals, a plurality of branch circuits controlled by said electronic relay, a synchronous printer element adapted to print desired intelligence corresponding to said indications, means for closing said branch circuits in predetermined sequence, and means other than said circuit closing means for terminating the current through said electronic relay upon ionization after a predetermined interval.

21. In telegraph printers, a typewheel adapted to be moved into two alternative printing positions, and shift means for said typewheel for shifting said wheel into one printing position in response to a received shift signal, and means for returning said typewheel to the other printing position independently of received signals.

HARRY J. NICHOLS.
